UNITED STATES PATENT OFFICE.

JOSEPH S. DUNCAN, OF CHICAGO, ILLINOIS, ASSIGNOR TO ADDRESSOGRAPH COMPANY, OF CHICAGO, ILLINOIS, A CORPORATION OF ILLINOIS.

TYPE-CHASE.

No. 906,397

Specification of Letters Patent.

Patented Dec. 8, 1908.

Application filed April 22, 1908. Serial No. 426,596.

To all whom it may concern:

Be it known that I, JOSEPH S. DUNCAN, a citizen of the United States, residing at Chicago, in the county of Cook and State of Illinois, have invented new and useful Improvements in Type-Chases, of which the following is a specification.

Circular letters are, to a considerable extent, printed in the offices of those who send them out and on machines designed for that particular purpose. There is a variety of these machines and in my Letters Patent No. 774,658 dated Nov. 8, 1904 and No. 774,912 dated Nov. 15, 1904 are disclosed machines which not only print the letter but also address it and affix the signature. Sometimes a number of forms are kept in stock for use on these machines, and one form may be used a great number of times with a change of one or more lines or a portion of a line. As these machines are often in charge of office boys or unskilled operators it is very desirable to provide for making such changes in a simple and easily understood manner.

25 The object of the present invention is to provide a chase in which the type form can be readily secured and which will permit changes therein to be easily and quickly made.

30 In the accompanying drawings Figure 1 is a plan view illustrating the invention. Fig. 2 is a sectional view on the line 2—2 of Fig. 1. Fig. 3 is a similar view showing a type holder and a spacing strip in the position of being arranged in or removed from the chase. Fig. 4 is a sectional view on the line 4—4 of Fig. 1.

The type 5 are first set up in suitable holders 6 and the latter are secured on the base 7 by angle clamping plates 8, 8' and adjusting screws 9. The type holders are provided at their ends with lips 10, 10', the lips 10' at one end being longer than the lips 10 at the other end. The clamping plate 8' which engages the lips 10' is preferably wider than the clamping plate 8 which engages the lips 10. Spacing strips 11 may be arranged between the type holders and they are similarly provided at one end with a short lip 12 and at the other end with a longer lip 12', corresponding to the lips on the type holders. The adjusting screws work in threaded openings 13 in the base and are made with cone shaped heads 9' to engage the bevel edge of openings 14 in the clamping plates.

55 In practice, the adjusting screws of each

clamping plate are loosened so that the long lip 10' of the type holder may be slipped beneath the clamping plate 8' and then the holder is laid flat against the base and adjusted endwise (to the left in the form illustrated) until the lip 10 is beneath the clamping plate 8. When all the holders, with or without spacing strips, are thus arranged on the base against the gage pins 15 and with their lips engaged beneath the clamping plates, the screws are tightened and the conical head of the screws bearing on the beveled edge of the openings in the clamping plates will draw the plates down to clamp the lips of the type holders and spacing strips securely against the base. To remove a holder the screws are loosened and the holder is moved endwise (to the right in the form illustrated) until the short lip 10 is clear of the clamping plate 8, as indicated by the holder 6' in Fig. 1. The free end of the holder can then be raised and the holder moved endwise (to the left) to withdraw the long lip 10' from beneath the clamping plate 8', as indicated by the holder 6" in Fig. 1 and Fig. 3. The spacing strip is inserted and removed in a similar manner.

My invention provides for inserting a holder containing a line of type, or a spacing strip, in a chase, and for removing the same from a chase, in a simple and expeditious manner which can be easily accomplished by an operator without especial skill or instruction. This can be done, also, without changing or disturbing the other holders and spacing strips except as it may be desired to readjust them. It is obvious that the invention can be embodied in a chase of any desired size and that rubber or metal or other type may be used. I have shown spacing strips in the form of wires and type holders in channel form but they may be otherwise constructed provided they have the lips contemplated by my invention.

What I claim and desire to secure by Letters Patent is:

1. The combination of a type holder, a chase comprising a base to receive the type holder, angle clamping plates each having a top part overlapping the top of the base to engage the end of the type holder and a side part to lie against the side of the base, and means operating in the sides of the base and through the sides of the plates and having beveled engagement with the sides of the

plates to secure the plates to the base and to adjust the top parts of said plates towards the base.

2. The combination of a type holder having a short lip at one end and a long lip at the other end, a chase comprising a base to receive the type holder, angle clamping plates at the sides of the chase to engage said lips, and means for adjusting said plates towards the base to secure the type holder to the base.

3. The combination of a type holder having a short lip at one end and a long lip at the other end, a chase comprising a base to receive said type holder, angle clamping plates at the sides of the chase to engage said lips, said clamping plates being proportioned in width to the length of the lips which they respectively engage, and means for adjusting said plates to secure the type holder to the base.

4. The combination of a type holder having a short lip at one end and a long lip at the other end, a chase comprising a base to re-

ceive the type holder, clamping plates to engage said lips and proportioned in width to the length of the lips which they respectively engage, said clamping plates having openings therein with beveled edges, and adjusting screws working in threaded openings in said base and having cone-shaped heads to engage the beveled edges of the openings in the clamping plates.

5. The combination of a spacing strip having a short lip at one end and a long lip at the other end, a chase comprising a base to receive said spacing strip, clamping plates to engage the lips on said strip and proportioned in width to the length of the lips which they respectively engage, and means for adjusting said clamping plates to secure the strip to the base.

JOSEPH S. DUNCAN.
